[57] CLAIM

The ornamental design for a meat tenderizer head, as shown and described.

DESCRIPTION

FIG. 1 is a perspective view of a meat tenderizer head according to the present invention with an attached handle shown in phantom lines.

FIG. 2 is a top view of the meat tenderizer head shown in FIG. 1, with an attached handle shown in phantom lines.

FIG. 3 is a bottom view of the meat tenderizer head shown in FIGS. 1 and 2.

FIG. 4 is a front view of the meat tenderizer head shown in FIGS. 1-3, with an attached handle shown in phantom lines.

FIG. 5 is a left side view of the meat tenderizer head shown in FIGS. 1-4, with an attached handle shown in phantom lines.

FIG. 6 is a rear view of the meat tenderizer head shown in FIGS. 1-5, with an attached handle shown in phantom lines.

FIG. 7 is a right side view of the meat tenderizer head shown in FIGS. 1-6, with an attached handle shown in phantom lines.

The broken lines are for illustrative purposes only and form no part of the claimed design.
